UNITED STATES PATENT OFFICE.

HENRY RUPPEL, OF CLEVELAND, OHIO.

VAPOR-BURNER STOVE.

SPECIFICATION forming part of Letters Patent No. 416,040, dated November 26, 1889.

Application filed June 21, 1889. Serial No. 315,112. (No model.)

To all whom it may concern:

Be it known that I, HENRY RUPPEL, of Cleveland, in the county of Cuyahoga and State of Ohio, have invented certain new and useful Improvements in Vapor-Burner Stoves; and I do hereby declare the following to be a full, clear, and exact description of the invention, such as will enable others skilled in the art to which it pertains to make and use it, reference being had to the accompanying drawings, which form part of this specification.

My invention relates to an improvement in vapor-burner stoves; and the objects of my invention are to dispense with the usual lighting-cup and substitute therefor a reservoir which is filled with packing, and through which air and gasoline are forced for the purpose of producing vapor, by means of which the central burner can be instantly lighted; to place upon the stand-pipe a generating-chamber which is divided by a partition into two separate and distinct chambers, and which has a perforated top, the inner chamber being fed with vapor by the central generating-burner and the outer one by the two end burners, the flame from the generating-chambers being used both to generate vapor for the central burner and to relight the end burners should they become accidentally extinguished at any time, and to do away with the ordinary needle-valves, which are operated by hand wheels or levers, and to substitute therefor endwise-moving grooved needle-valves, which are operated by pinions, and which can be changed when they become worn at any one point.

Figure 1 is a front elevation of a vapor-burner stove embodying my invention, the name-plate and the levers connected to the operating-stems being removed in order to show the parts more clearly. Fig. 2 is a side elevation of the same, the end burner being removed. Fig. 3 is a plan view, a portion of the central burner being removed. Figs. 4 and 5 are detail views of the slotted name-plate and the levers for operating the valves which control the flow of vapor to the end burners. Fig. 6 is a plan view of the generator.

50 A represents the pipe which conducts gasoline from the tank to the central burner, and

B the stand-pipe, upon which the central generating-burner C is placed. This stand-pipe is connected to a T-shaped pipe or casting D, which is connected to the pipe A at 55 opposite ends or sides, has two connections extending at right angles thereto for the reception of the hollow valve-stem and the reservoir, and another connection d, which extends vertically, and to which the stand-pipe 60 B is screwed. Leading from the top of the stand-pipe is the vapor-pipe E, which is provided with a controlling-valve F for regulating the flow of vapor to the central burner C, and from which pipe extends at an angle 65 the pipe G, which has its outer end e turned at an angle so as to be in line with the pipe H, which extends from the central burner C, and which end e contains the needle-valve, which controls the flow of vapor into the 70 pipe H. This needle-valve is regulated in the first instance by means of a screw-plug I, and which is not afterward changed except when it is desired to clean the needle or the pipe, or under similar circumstances. This 75 needle is thus locked up out of the way, so as not to be injured by persons operating it unnecessarily. The plug-valve F is intended to control the flow of vapor directly from the stand-pipe, and the needle-valve is not to be 80 operated after it is once adjusted.

Heretofore lighting-cups have generally been employed for starting the stove in operation; but these are objectionable on account of the smoke and fire and the blackening of 85 the stove wherever the flame touches. In order to do away with this lighting-cup, the reservoir J is used, which is screwed upon the arm K, which extends from the coupling D. This reservoir is filled with a 90 packing of any suitable porous material, and extending from the top of the reservoir is the pipe L, which is provided with a stop-cock to control the flow of vapor or gasoline through it, and which pipe has its outer 95 end reduced somewhat and bent at such an angle as to discharge directly into the pipe H of the central burner C. Extending from the coupling D, in a direct line with the pipe K, is a second internal screw-threaded pipe 100 M, through which the hollow valve-stem passes. To the outer end of this valve-stem

N is secured a bulb or other air-forcing mechanism Q, and connected to the stem is the operating-lever O, by means of which the stem can be revolved. The inner end of this stem 5 N forms a valve and fits into a seat made in the inner end of the pipe K for the purpose of regulating the flow of air and gasoline into the reservoir J. When the stem N is given a quarter-turn, so as to move its inner end 10 from off its seat in the end of the pipe K, and the bulb Q or other forcing mechanism is operated, air and vapor are forced into the reservoir J, and from this reservoir, when the stop-cock in the pipe L is opened, the vapor 15 passes into the central generator, and from which burner the vapor is lighted. A few operations of the bulb or other air-forcing mechanism will force a sufficient supply of air into the reservoir to supply vapor enough to start 20 the central generator, and then the stem N should be given a quarter-turn by means of the lever O, so as to close the supply of gasoline to the reservoir J. The stop-cock is placed in the pipe L, so that the flow of vapor 25 from the reservoir can be shut off whenever so desired.

By means of the construction above described vapor is always held under pressure in the reservoir, or can be instantly generated, so that the central burner can be lighted 30 like gas; thus enabling the ordinary lighting-cup to be entirely dispensed with.

Extending downward from the central burner C is a pipe R, which conducts a portion 35 of the vapor from the mingling-chamber into the inner chamber S of the generating-chamber. This generating-chamber T is divided by a vertical partition U into the outer chamber V and the inner chamber S, and the 40 two chambers are provided with a perforated cover a, through which the vapor escaping from one or both of the chambers burns. The inner chamber S is in contact with the upper end of the stand-pipe; but the heat from this 45 chamber is intended to vaporize the fuel in the stand-pipe B and to heat the two supply-pipes W, through which vapor passes to the end burners X. The two chambers S V have no communication with each other, and while 50 the chamber S is in use all the time that the central burner is being used the outer chamber V is only brought into use when one or both of the end burners X are being used.

The flow of the vapor from each of the 55 pipes W is controlled by an endwise-moving needle-valve Y, which has a series of vertical grooves made in its stem, and which valve is operated by the pinion Z, the teeth of which catch in the grooves and move the needle back and 60 forth as the pinion is caused to partially revolve by the stem A'. Each of the valves Y is grooved circumferentially in its stem, so that when any one part becomes worn by the 65 operation of the pinion Z the valve can be turned partially around, and thus bring a new surface into play. This construction also enables the valve to be removed and replaced,

so as to present a new surface at the point in case the valve should not fit perfectly to its seat.

If the grooves or teeth upon the valve-stem were made upon one side only, the valve would always have to be used in just one position, because the pinion cannot operate it at any other point. The vapor escapes from the end 70 of the pipe W into the conducting-pipes B' of the end burners X. Extending parallel with the conducting-pipes B' and connecting with the outer chamber V of the generator T, at one end and the bottom of the outer burners X, are the pipes C', through which a portion of the vapor from each end burner X passes backward to the generator, and, escaping from the top of the chamber V, is burned 75 at that point. Extending from each end burner X, and having its inner open end placed just above the top of the chamber V, is a conducting-pipe D', through which a portion of the vapor escaping from the end burner or a portion of the vapor escaping 80 from the chamber V passes. Should the end burner become accidentally extinguished, a portion of the escaping vapor will be caught 85 in the end of the pipe D' and pass backward toward the generator at the same time that a portion of the lighted vapor from the chamber V will enter its inner end. The consequence is 90 that flame will follow the gas through the pipe D' and light the extinguished burner; or should the flame arising from both chambers 95 of the generator become extinguished, a portion of the escaping vapor will be caught by the inner end of the pipe D' and be carried out toward the end burner, at which point it will be ignited, and then the flame will be 100 passed backward through the pipe D' for the purpose of relighting the generator. In this manner, should any one or two of the burners 105 become extinguished they will be automatically relighted by having the flame pass through the pipes D', as above described. Should the central burner become extinguished at any time and the generator remain lighted, the flame will pass up around 110 the sides of the burner C and relight. 115

By the construction above described I have, by dividing the chamber T into two annular chambers, combined the ordinary flame of the inner chamber S with the hotter flame of the mingled vapor and air from the outer chamber. In case the central burner alone 120 is used the ordinary flame from the chamber S is sufficient to generate the vapor and the hotter flame is dispensed with.

The stems A', having the pinions Z secured to their inner ends, pass through suitable packing-boxes F', and have their outer ends preferably supported in suitable bearings formed upon the inner side of the slotted name-plate G', and to the outer ends of these 125 stems A' are secured the cranks H', which extend upward and have the operating-levers I' pivoted to them, the levers I' being made to extend horizontally through the slot J'

formed in the name-plate. These slots are preferably made curved, and at one end of each slot there is made a notch or shoulder L', behind which each handle or lever I' drops for the purpose of locking the valve Y in position when closed. These notches or shoulders are formed so that the handle or lever cannot be accidentally moved in such a manner as to open the valves Y and permit an escape of vapor by having the dress or some object strike against them. The other end L'' of each of the slots from the shoulders or recesses L' are suitably enlarged, so as to allow the levers or handles to drop down therein, and thus hold the valves open after the burners have been lighted.

Having thus described my invention, I claim—

1. The combination, with a vapor-burner, of an air-forcing device connected to the supply-pipe which extends from the tank, a reservoir also connected to the supply-pipe and into which air and gasoline are forced, and a pipe which extends from the top of the reservoir and conducts the vapor to the burner, substantially as shown.

2. The combination of a vapor-burner connected to a supply-pipe, a reservoir filled with a suitable porous material and also connected to the supply-pipe, an air-forcing device, and a hollow valve-stem connected to the air-forcing device and which controls the supply of mingled air and gasoline into the reservoir, and a pipe extending from the top of the reservoir and which conducts the vapor generated in the reservoir to the burner, substantially as set forth.

3. The combination of the supply-pipe extending from the tank, the stand-pipe, and the burner placed upon the top of the stand-pipe, with an air-forcing device connected to the outer end of a hollow screw-threaded valve-stem, a lever for operating the valve-stem, a pipe leading from the supply-pipe and provided with a valve-seat to receive the end of the valve-stem, a reservoir into which the mingled air and gasoline is forced by the air-forcing device, and a pipe for conducting the vapor to the burner, substantially as specified.

4. The combination of the stand-pipe, a vapor-burner mounted thereon, a heating-

chamber secured to the stand-pipe below the burner and having a perforated top, a pipe R, which connects the burner with the heating-chamber, a side burner, and a pipe D', which extends from the side burner to the heating-chamber and is open to the air at both of its ends, substantially as shown.

5. The combination of the central generating-burner, the stand-pipe, a heating-chamber provided with a perforated top and divided into two chambers or compartments, a pipe which extends downward from the central generator to supply the inner compartment with vapor, the end burners provided with conducting-pipes, the supply-pipes W, provided with regulating valves or needles, the pipes C', which conduct a portion of the vapor back from the end burners to the outer chamber of the generator, and pipes which conduct flame back and forth between the end burners and the generator, substantially as described.

6. The combination of the central burner, the stand-pipe upon which it is placed, the generator placed upon the stand-pipe, the end burners, pipes which conduct the flame back and forth between the end burners, and generator-pipes extending from the burners to the generator, the generator being provided with a perforated top and divided into two chambers, substantially as set forth.

7. The combination of the stem A', provided with a crank, arm, or lever H, the name-plate G', provided with bearings for the outer ends of the stem A' and having the slot J', with an offset L' at one end and a suitable enlargement L'' at the other, and the handle I', pivoted at the outer end of the arm or lever H, substantially as shown.

8. The combination of the cranked stems provided with pinions at their inner ends, the supply-pipes W, extending outward from the central generator, and the circumferentially-grooved needle-valves, whereby the valves can be rotated or changed in position, substantially as shown.

In testimony whereof I affix my signature in presence of two witnesses.

HENRY RUPPEL.
